UNITED STATES PATENT OFFICE

2,182,531

GAME

Roy A. Beard, Oaktown, Ind.

Application April 17, 1937, Serial No. 137,564

1 Claim. (Cl. 273—131)

As games of pure skill playable on game-boards have long been popular and as many people prefer them to games of chance, I have devised this invention in order that practical and entertaining games of pure skill may be played, providing for the use of make-believe money or other numerical or financial counters in keeping constantly changing scores as the games progress.

10 A more specific object is to make possible the simulation of business transactions, money transfers, humorous situations, or other matters of interest to the players in real life, in such ways that games of skill employing these features may be played.

Another object is to provide, in games of skill, more and greater chances of reaching a plurality of major as well as minor goals.

Another more specific object is to provide in games of skill, for frequent, definite changes in scores, and to make convenient the use of counters, preferably make-believe money, to record the extent and directions of these score changes as the games are played.

25 With the foregoing and other objects in view which will become apparent as the description proceeds, the invention resides in the novel subject matter hereinafter described and claimed, description being accomplished by reference to the accompanying drawings.

Fig. 1 is a plan view of a game-board disclosing the principal preferred features.

Fig. 2 is a view similar to Fig. 1 but showing certain variations.

35 Fig. 3 is an enlarged plan view of the central portion of the board of Fig. 2.

Fig. 4 is another plan view showing a still further variation of the game-board.

Fig. 5 is a plan view representing some of the 40 make-believe or "stage" money.

Fig. 6 is a perspective view showing some of the playing pieces or "men".

The game comprises briefly, a game-board having certain characteristics to be hereinafter 45 described, a plurality of playing pieces or "men", and a plurality of financial or numerical counters, preferably in the form of make-believe or "stage" money.

The game-board is of any suitable material 50 or size. It is square or approximately so and its four edges are to be disposed toward four players, respectively. As hereinafter more definitely described, the board is provided with four varieties of playing squares allotted one variety to each of the four players, said varieties each hav-

ing the same number of playing squares, and in order to conspicuously identify the squares belonging to any player, the great majority are uniformly colored. A majority of at least two-thirds of the squares are of four clearly distinguishable essential powered varieties, the squares of one essential variety being right-side-up to one of the four sides or edges of the playing field, and the squares of the other three essential powered varieties being right-side-up to the other three sides or edges of said playing field, respectively, the right-side-up positions of the squares of any essential variety being indicated by the right-side-up position of printed matter or indicia appearing within the same. 15 Thus, with four colors, brown, red, green, and white, for example, and with the printed matter or designs in four different right-side-up positions, the playing squares of the four players may be at all times conspicuously identified. The 20 squares of the four essential varieties are distributed over the entire playing field without regard to any checkered or alternate design and in such relation that some of the squares of the four different essential varieties are provided in 25 any important area or section into which the board may be divided by imaginary lines, such as fourths or thirds, in such relation that the squares of the four varieties adjoin and intermingle in any such area or section of the board. 30 Three forms of the board are disclosed. One at 10 in Fig. 1, another at 10^a in Figs. 2 and 3, and a third at 10^b in Fig. 4, and they will be fully explained hereinafter.

The playing pieces or "men" may be of any 35 desired size, shape and material to be easily moved by the players without liability of rolling, and disks or the like such as those shown at 11 in Fig. 6 will suffice. There may be any desired number of these "men" (preferably forty-eight) 40 and they are equally allotted to the four players, and in order to identify the "men" of any player with his playing squares, said "men" are preferably given the same color as said squares. As brown, red, green and white have been used as 45 examples of identifying colors which may be used, these colors have been represented on the aforesaid playing squares, and on the "men" 11. Although only one "man" of each color is shown, there may be any selected number, twelve of 50 each being preferred.

The financial or numerical counters, preferably consist of make-believe or "stage" money representing the currency of any country in coins, bank notes, treasury notes, checks, etc. 55

of any desired denominations. For example, "stage money" 12 has been shown in Fig. 5 representing U. S. currency in denominations of \$10, \$50, \$100, \$500 and \$1000. While only one note or the like of each denomination is shown, there may be as many as desired, and the total represented may be any amount, for instance, \$50,000. At the start of the game, say \$20,000 of the "money" is divided equally among the 10 four players ("\$5000" to each) and the rest is kept in the "treasury" by any one of the players who may be selected as the "treasurer".

The object of each player is to obtain as much money as possible, both from his opponents and 15 from the "treasury", and the game ends when any player loses all of his "money" or has played with and lost all of his "men", the winner being the one having the most "money" on hand. However, before the way of playing can be explained, a definite description of one form of 20 the board will be necessary and as I now consider the board 10 of Fig. 1 as preferred, the description will be directed primarily thereto.

The four edge portions of the board 10 may 25 bear identifying names, numbers, letters, titles or the like to be assumed by the four players respectively. The titles "Doctor", "Banker", "Politician" and "Producer" are shown and for 30 purposes of explanation, the players will be called by these titles.

The major portion of the board is divided 35 into a plurality of adjoining playing squares. In the embodiment under consideration, there are twelve horizontal rows of these squares with each row containing twelve squares. For descriptive purposes, the twelve rows are identified by the numbers 13 to 24 but it is impracticable to apply reference numerals to the individual squares in view of the printed matter and color- 40 indicating lines appearing thereon. The squares are allotted equally to the four players and any player's squares are scattered over the board. Most of these squares are conspicuously identified by colors, although two in row 16 and two 45 in row 21 are distinctively identified by heavy outlines and heavy parallel cross lines. The colored squares of "doctor" are represented as being brown, those of "banker" red, those of "politician" green and those of "producer" white, 50 although any other colors could be used if desired.

All of the squares belonging to any player are numerically or financially powered, in the present disclosure by symbols representing U. S. dollars, 55 ranging from say \$10 to \$600. All of the financial symbols on the squares of any player are so printed that they appear "right-side-up" only to him. All of the colored squares preferably bear wording to inject items of interest and 60 humor into the game as will be seen by reading some of said wording, the wording for "doctor" being such as would apply to a doctor, that for "banker" being selected to apply to a banker, etc. All of this wording on the squares belonging 65 to any player is so printed as to appear "right-side-up" only to said player.

The four distinctively identified squares above mentioned (two in row 16 and two in row 21) belong one to each player and the financial 70 power of all is the same—'\$200" for example. The printed matter on each of these squares is distinctive and is the same for all, "bank nite" being illustrative of printing which may be used. As with the colored squares, the financial power 75 and other printing on these "bank nite" squares,

is readable "right-side-up" only to the respective owners of said "bank nite" squares.

The four central squares, two in row 18 and two in row 19, belong one to each player and they are specially identified, for instance by printing 5 "Pay square" on each. All of these "pay squares" are financially powered equally, for example by printing \$500 thereon. The financial power and the other printing on each of these "pay squares" is such as to appear "right-side- 10 up" only to the owner.

While the "bank nite" squares, the "pay squares", and the various other squares above described, all constitute playing squares over which the "men" 11 are moved, said "bank nite" 15 squares and said "pay squares" also constitute goals which dictate amounts of money to be paid from "the treasury" under certain conditions. Additional goals 25 and 26 are provided in the 20 present disclosure, disposed along the edge portions of the board 10 and these goals 25 and 26 determine other amounts to be paid from the holdings of the players themselves, under certain other conditions, all of which will be hereinafter explained.

The goals 25 and/or 26 may be termed "Pension goals" and they are allotted equally to the four players. They may be of any desired design and may be associated or connected with the outside squares of the main playing field 30 in any preferred way. In the present showing, the goals 25 are connected with these outside squares by short lines and the goals 26 adjoin the outer ends of said goals 25. Preferably, the goals 25 are narrower than the squares with 35 which they are associated, so that they will not lose their identity even when associated with adjoining squares, as shown. All of the goals 25 and 26 have "pensions" printed thereon, for example \$500 and \$1000, and the goals of any 40 player are identified by giving them the same color as that of his playing areas and his "men" 11. The "pensions" are so printed that those on the "pension goals" of any player will appear "right-side-up" only to him. In the present 45 showing, there are eleven "pension goals" 25 and eleven "pension goals" 26 at each edge of the board, and each player owns all eleven of the goals 26 at the edge of the board opposite that at which he sits, owns six of the goals 25 at the 50 edge of the board to his left, and owns five of the goals 25 at the edge of the board to his right, making twenty-two goals available to his "men" 11 unless guarded by the "men" of his opponents. All twenty-two of these "pension 55 goals" owned by any player are reserved for the exclusive use of his own "men", being the only spaces on the entire board onto which opponents cannot move their "men", it being of course understood however, that no player can move 60 onto any square already occupied.

The rules of the game may be such as to allow each player to start with any given number of "men" 11 upon the board and said rules may designate where said "men" are to be placed 65 before play begins. For illustrative purposes, five "men", 11, for each player will be specified as the number to be used at the start and as the maximum number which any player may have upon the board at any one time, and five of each 70 player's own playing squares will be designated as starting squares upon which to initially place said five "men". These starting squares may be considered as being the corner square to the player's right, the next two squares interposed 75

diagonally between said corner square and said player's "bank nite" square, and the two central squares in the outer row toward said player. For example, the starting squares of "doctor" 5 are those bearing "chiggers \$20", "medical examination \$70", "radioitis \$100", "falling hair \$80" and "stiff neck \$20". If desired, the starting squares could, of course, bear some symbol, 10 indication or the like identifying them as such, but the rules to accompany the game may well be relied upon instead, or the players themselves may decide upon the starting squares to be used.

To play the game, the four players sit at the four edges of the board 10 and assume the titles 15 "doctor", "banker", "politician" and "producer". All playing squares and goals containing printed matter appearing "right-side-up" to any player, belong to said player, and the color of said playing squares and goals determine the color of the 20 "men" 11 which said player is to use. Each player is given a predetermined number of "men" (preferably twelve) of the proper color, and he occupies his starting squares by placing a "man" 25 on each of said squares. It will be recalled that the starting squares of any player are the corner square to his right, the two squares diagonally interposed between this corner square and his "bank nite" square, and the two central squares 30 on the outside row next to the player. There being five such starting squares for each player, he places five of his "men" 11 on them and keeps the remainder in reserve.

The "money" 12 is uniformly distributed to the players by one of them selected as the 35 "treasurer". He gives say "\$5000" to each player and keeps the rest in the "treasury" which may well be a small table or a chair within convenient reach.

It is not important which player moves first 40 or whether the player to his right or to his left moves next but if "doctor" for instance is the first to move, "banker" the second, "politician" the third and "producer" the last, the same order is to be maintained throughout the duration of 45 the game. Any player may move any of his "men" in any available one of eight directions—up, down, right, left, diagonally up to right or left, and diagonally down to right or left, and he may jump the "men" of any of his three 50 opponents. A mere move from any square to an adjoining square is one complete move and the player must await his next turn before moving again. However, if he jumps, he of course advances further and at the same time captures the "man" or "men" which he has jumped. 55 When jumping two or more "men" at one play, it is not necessary that all jumps be in the same direction and jumping is always optional with the player. Whenever a "man" 11 is jumped 60 and removed from the board, the player who has just lost it may if he so desires, place another "man" on the board from his reserve, when his next turn arrives, but such placing must be upon one of his starting squares and constitutes 65 a move. Each time a player occupies an opponent's square by merely moving a "man" 11 onto the same, he must pay that opponent the amount indicated on the newly occupied square. Also when making a single jump and landing on 70 an opponent's square, the player must pay that opponent the amount indicated on said square, but the owner of the jumped man must pay the player "\$500". When continuously jumping two or more times, the player pays only for the square 75 on which he finally lands, but the opponent or

opponents pay "\$500" for each jumped "man". Any time a player moves onto his own "pay square" (see the four "pay squares" in rows 18 and 19) from more than two squares away, the "treasurer" must pay him from the "treasury" 5 the amount indicated on said "pay square" ("\$500"), but whenever a player moves onto an opponent's "pay square", neither pays nor receives anything. When a player moves onto an opponent's "bank nite" square from more than 10 two squares away, the "treasurer" must pay said player from the "treasury", the amount indicated on said opponent's "bank nite" square ("\$200") but when a player moves onto his own "bank nite" square, he neither receives nor loses 15 anything.

It will be recalled that each player owns a number of "pension" goals 25 and 26, that number being the eleventh goals 26 across the board from him, five of the goals 25 to his right, and 20 six of the goals 25 to his left. A player cannot jump into a "pension" goal but must move into the same from the outside playing square associated or connected therewith. In order to reach 25 any of his goals 26, a player inevitably crosses one of an opponent's goals 25 when the goals are placed as herein disclosed, but nothing is gained nor lost by such crossing and it is of course possible to so arrange the goals that it would 30 not be necessary for a player to cross another's goal to reach his own.

The "pension" goals 25 and 26 owned by any player, are for his exclusive use and he may avail himself of them as much as possible. Whenever 35 a player moves one of his "men" 11 onto one of these goals, that "man" is removed from the board and "pensioned", that is the opponent seated at the edge of the board at which the "pension" was gained, must pay the player a "pension" corresponding to the amount printed 40 on the goal upon which the "pensioning" was achieved. Furthermore, if the player receiving this "pension" has already received one or more "pensions", these previously received "pensions" must be again paid in full by the same person 45 paying the "pension" just received. The "treasurer" takes care of all "pensioned" "men" 11 as soon as removed from the board. He places all which have earned a "\$500 pension" on a "\$500 bill" of the "money" 12, and all which have 50 earned a "\$1000 pension" on a "\$1000 bill". He can then determine at a glance the gross "pension" due any player whenever he earns another "pension".

Each player should obviously endeavor to use 55 his own playing squares as much as possible, to avoid payment to opponents; should seek his own "pay square" (paying "\$500" from the "treasury"); should seek his opponent's "bank nite" squares (paying "\$200" from the "treasury"); should seek his own "pension" goals 25 and 60 26 (winning "pensions" of "\$500" or "\$1000" and also gaining repayment of any "pensions" previously received); and should constantly endeavor to block the plays of opponents and to 65 capture their "men", each captured "man" earning him "\$500".

The game stops when any player is out of "money" or out of "men" and the winner is the 70 one then having the most "money" on hand.

The board 10^a of Figs. 2 and 3 is provided with a plurality of distinctively identified starting squares upon which to place the "men" at the start of the game and whenever a "man" is added to replace a jumped "man", said starting 75

squares being shown solid black. The powered squares of the four major varieties are 60 percent or more of the total number provided, and the minor varieties of distinctively identified or starting squares are 40 percent or less of the total number. They are so arranged that sets of six of them appear in the form of pyramids in the four quarters of the board when the latter is derived by two imaginary crossed lines extending diagonally from corner to corner of the board.

Instead of having four "bank nite" squares as in the board 10 of Fig. 1, the board 10^a of Figs. 2 and 3 possesses one central "bank nite" square useable by all of the players. This square may also bear the titles or the like to be assumed by the players and it is equally right-side-up to all four edges of the board.

There are more squares on the board 10^a of Figs. 2 and 3 than on the board 10 of Fig. 1, thirteen rows of thirteen squares each, being shown. More of the "pension" goals 25^a and 26^a are also shown. Then too, the "pay squares" are differently located, the third square in from the center of each edge of the board being a "pay square". Aside from the differences mentioned, the board 10^a of Figs. 2 and 3 is so similar to the board 10 of Fig. 1 as to require no further description. The same rules apply except that six "men" may be had upon the board at any time by each player and the single "bank nite" square acts to the advantage of any player moving a "man" onto it. The owner of any "man" moved into this "bank nite" square receives \$100 from the "treasury".

The board 10^b of Fig. 4 is very similar to that of Figs. 2 and 3. The starting squares are distinctively identified and disposed in sets which radiate from the central square to the four

corners of the board, being shown solid black. The powered squares of the four major varieties are 60 percent or more of the total number provided, and the minor varieties of distinctively identified or starting squares are 40 percent or less of the total number. There is no "bank nite" square, but "pay squares" are provided, located as in Fig. 2, the third square in from the center of each edge of the board being a "pay square." The central square is neither powered nor owned but preferably displays the titles or the like to be assumed by the players.

The invention may be embodied in numerous forms other than those shown and it is therefore to be understood that the present disclosure is illustrative rather than limiting.

I claim:

A gameboard having a square main playing field and a margin surrounding the same, said main playing field being composed of at least four clearly distinguished varieties of playing areas, said playing areas of one of said varieties having value indicia right-side-up to one edge of said playing field, the playing areas of the other three varieties having value indicia right-side-up to the other three edges of said playing field respectively, and means in said margin outside said main playing field defining goals of four different varieties clearly distinguished in the same manner as said playing areas and disposed along the four edges of said playing field, one variety of said goals having goal values marked thereon right-side-up to said one edge of said main playing field, the other three varieties of said goals having goal values marked thereon right-side-up to said other three edges of said main playing field respectively.

ROY A. BEARD.
